UNITED STATES PATENT OFFICE.

ALVIN W. SPENCER AND FRANK A. FALCONER, OF WESLACO, TEXAS; SAID SPENCER
ASSIGNOR TO SAID FALCONER.

BASKET TOP.

Application filed August 23, 1926. Serial No. 130,960

The present invention relates to an improved basket top.

Shipping baskets are now made with a top which is constructed of thin strips of wood arranged in circular form which are either nailed together or fastened together with wire clips. A heavier piece of wood is fastened to the rest of the top and extends about one or two inches beyond the edge of the basket, slipping under the handles.

In shipment, it often happens that the basket is spread and the projection slips out from under the handle and the basket is left open, or it may be that the strip itself becomes broken and allows the contents of the basket to come out.

The important object of this invention is twofold; first, it prevents the basket from spreading; and second, in the event the wooden strip breaks, the lid will be intact and in place.

Another very important object of the invention lies in the provision of an improved basket top of this nature which is exceedingly simple in its construction, strong and durable, inexpensive to manufacture, efficient and reliable, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

35 In the drawings:—

The figure is a perspective view of a basket and top therefor embodying the features of our invention.

Referring to the drawing in detail, it will be seen that the letter B denotes a basket having a top T. This top T as is usual, includes a plurality of strips 5 arranged in a circular formation, that is to produce a round top. A bar 6 of heavier material than the strips 5 is fastened to the top to extend diametrically thereof and to have a length greater than the diameter of the top T so as to project through bails 7 which form the handles of the basket. My improvement lies in the provision of a strip of ductile metal 8 which is fastened longitudinally on top of the bar 6 and has its ends free so that they may be bent over the bight portions of the bails 7,

thus preventing the accidental displacement of the top T from the basket and also preventing the basket from spreading.

It is thought that the construction, utility, and advantages of this invention will now be clearly understood by those skilled in this art without a more detailed description thereof. The present embodiment of the invention has been disclosed in detail merely by way of example, since in actual practice it attains the features of advantage enumerated as desirable in the statement of the invention and the above description.

Numerous changes in the details of construction may be resorted to without departing from the spirit or scope of the invention as hereinafter claimed or sacrificing any of its advantages.

Having thus described our invention, what we claim as new is:—

1. In combination, a basket, a top on the basket, said top being provided with a bar 75 extending beyond the edges thereof and the edges of the basket, said basket being provided with bail handles through which the ends of the bar extend, and a strip of ductile material fastened longitudinally on top of the bar to extend co-extensively therewith and having its ends freed from the bar so that they may be curved upwardly and over the bails.

2. A top for a basket including a bar having a length greater than the diameter of the top to extend beyond the edge thereof and a strip of ductile material fastened to the bar co-extensive therewith and having its ends disengaged and free from the bar so that 90 they may be bent upwardly in engagement with the bail of a basket through which the ends of the bar are adapted to extend.

3. In combination, a basket, a cover for said basket, said cover being provided with a 95 bar extending beyond the edges thereof and the edges of the basket, said basket being provided with bail handles through which the ends of said bar extend, and a strip of ductile material fastened longitudinally on top 100 of said bar to extend co-extensively therewith and having its ends free from the bar so that they may be curved upwardly and over the bail handles.

4. The combination with a cover fastening slat; of a combined reinforce and fas-

tener comprising a metal member to overlie and extend throughout the length of said slat, the ends of said member being bendable to form attaching loops.

5. The combination with a container having upstanding handles, a slat to extend across said container and under said handles,

a reinforcing strip overlying said slat and having bendable ends for interlocking engagement with the handles.

10

In testimony whereof we affix our signatures.

FRANK A. FALCONER.
